Filed Mar. 29, 1973, Ser. No. 346,178

Term of patent 14 years

Int. Cl. D25—99

FIG. 1 is a perspective view of a roof penetration member embodying our new design;

FIG. 2 is a top plan view of the roof penetration member of FIG. 1;

FIG. 3 is a bottom plan view of the roof penetration member shown in FIGS. 1 and 2;

FIG. 4 is an end view of the roof penetration member shown in FIGS. 1-3, the other end being a mirror image of the end shown in FIG. 4; and

FIG. 5 is a front, elevational view of the roof penetration member shown in FIGS. 1-4, the back, elevational view of the roof fixture being a mirror image of the front, elevational view shown in FIG. 4. The view of FIG. 5 shows the member in its environment.

We claim:

The ornamental design for a fixture for a roof penetration member, as shown and described.
